CLAIM

The ornamental design for a wireless earbud, as shown and described.

DESCRIPTION

1. Wireless earbud

1.1 : Perspective

1.2 : Front

1.3 : Back

1.4 : Left

1.5 : Right

1.6 : Top

1.7 : Bottom

The evenly-spaced broken lines depict portions of the wireless earbud that form no part of the claimed design; the dash-dot broken lines define the boundary of the claimed design and form no part thereof; reproduction 1.1 is a front perspective view of the wireless earbud; reproduction 1.2 is a front view thereof; reproduction 1.3 is a back view thereof; reproduction 1.4 is a left side view thereof; reproduction 1.5 is a right side view thereof; reproduction 1.6 is a top plan view thereof; reproduction 1.7 is a bottom plan view thereof; the present design is a right wireless earbud; the left earbud is a mirror image thereof.

1 Claim, 7 Drawing Sheets
